United States Patent Office

Des. 192,760

Patented May 8, 1962

192,760

FONT OF DISPLAY LETTERS

Dean H. Reynolds, Rochester, N.Y., assignor to Eastman Kodak Company, Rochester, N.Y., a corporation of New Jersey

Filed Oct. 21, 1960, Ser. No. 62,565

Term of patent 14 years

(Cl. D64—12)

FIG. 1

FIG. 1a

FIG. 2

FIG. 2a

FIG. 3

FIGS. 1 and 1a illustrate the upper case of a font of display letters showing my new design;

FIGS. 2 and 2a illustrate the lower case letters thereof; and

FIG. 3 is an enlarged, detailed fragmentary view of one edge of one of the letters, same being common to all the letters.

I claim:

The ornamental design for a font of display letters, substantially as shown and described.
